UNITED STATES PATENT OFFICE.

BÉLA SCHAEFER, OF FRANKFORT-ON-THE-MAIN-BOCKENHEIM, GERMANY, ASSIGNOR
TO THE FIRM OF HARTMANN & BRAUN A. G., OF FRANKFORT-ON-THE-MAIN, GER-
MANY.

VAPOR ALTERNATING-CURRENT RECTIFIER AND SIMILAR APPARATUS.

1,223,428.

Specification of Letters Patent. Patented Apr. 24, 1917.

Application filed March 2, 1912, Serial No. 681,192. Renewed June 15, 1914. Serial No. 845,296.

To all whom it may concern:

Be it known that I, BÉLA SCHAEFER, a citizen of the German Empire, and residing at Frankfort-on-the-Main-Bockenheim, Province of Hesse-Nassau, in the Kingdom of Prussia, Germany, have invented certain new and useful Improvements in Vapor Alternating-Current Rectifiers and Similar Apparatus, of which the following is a specification.

This invention relates to mercury rectifiers of the general type set forth in my co-pending application filed March 1, 1912, and bearing Serial Number 680,815. It has been found in practice that in the operation of high capacity rectifiers of this class, much importance attaches to the manner in which the electrodes are distributed with relation to the space within the container. In apparatus of this class having glass bulbs, the attempt has been made to obviate the difficulties arising from ineffective distribution of the electrodes by curving the side branches of the bulbs and placing the electrodes therein. However, the arrangement of the anodes in a metal container is difficult to effect in this manner as these metal containers preferably have a cylindrical body through the top of which the anodes are introduced into the vacuum chamber.

The principal object of the present invention is to improve the distribution of the anodes in such metal containers. Heretofore, in order to protect the anodes from the injurious action of the flame arising from the cathode, screens or deflectors have been employed but when these screens are placed between the single anode or grouped anodes in the axis of the cylinder and the cathode, the arc tends to waver from side to side of the screen and owing to this unequal distribution, the wall of the vessel will be unequally heated and to an undesirable extent. Furthermore, when the anodes are arranged in a closed group, efficiency of the apparatus is greatly diminished by the mutual heating thereof.

In accomplishing the objects of the invention, the anodes are not grouped together in the axis of the vessel but are arranged in the shape of a circle or polygon in proximity to the cylindrical wall of the vessel so that the space immediately about the axis is left

free. By this arrangement, a relatively large number of anodes may be utilized and by positioning the cathode in the axis of the vessel, the arc paths will be of equal length and consequently of substantially equal resistance. Furthermore, the space between the anodes can be utilized in various manners, as for instance, by inserting cooling coils, thus increasing the condensation of the mercury vapor and consequently the efficiency of the apparatus.

In carrying out this invention, it will be found that the arrangement diminishes the mutual heating and short circuiting of the anodes while at the same time the paths of the arcs naturally unite to form a common arc adjacent the cathode and thus the disadvantage arising from the divergence or splitting of the arc in the old manner is obviated.

In the accompanying drawings, like characters of reference indicate like parts in the several views, and:

Fig. 1 is a diagrammatic elevation of a device as constructed in accordance with this invention.

Fig. 2 is a diagrammatic cross-section thereof.

Fig. 3 is a vertical section through one form of the apparatus showing a screen used in connection therewith.

Fig. 4 is a modification of the apparatus shown in Fig. 3 showing a different form of screen.

Fig. 5 is a vertical section showing a modified form of apparatus using a single cooling element.

Fig. 6 is a plan of the apparatus shown in Fig. 5.

Fig. 7 is a modification employing a plurality of cooling elements.

Fig. 8 is a plan of the modification shown in Fig. 7.

Fig. 9 is a plan showing a modified distribution of the anodes.

Fig. 10 is a diagrammatic view showing the application of the invention to a six-phase rectifier.

Fig. 11 shows a modified form having the anodes led in through the bottom.

In the various forms herein shown, the anodes are indicated at $-a_1-$, $-a_n-$, and the cathode is represented at $-k-$ and the bottom of the casing at $-t-$. In the form

shown in Fig. 3, the cathode has dipping therein a screen n having an opening adjacent the bottom of the screen and this bottom is in the form of a constricted neck 5 while the body of the screen surrounds the anodes between the wall w and said anodes. The anodes in this form are arranged close to the wall w in circular formation being all equally spaced from the 10 axis; and the same arrangement of anodes and cathode is true of the form shown in Fig. 4 but in this form the screen n is shortened and the constricted neck omitted, the bottom of the screen being funnel-shaped 15 and having a centrally-disposed opening. Immediately below this opening, there is a cup c of insulating material which rests on the floor, or bottom of the container and is provided with openings in its side wall 20 for the passage of the mercury therethrough. In the arrangement shown in Fig. 5, the anodes, here terminating in the projecting ends d , are arranged in two concentric circles about a cooling tube r which is further 25 protected by a screen o_1 concentric with a screen o_2 which is spaced at its lower end above the bottom t as is the screen n of Fig. 4. Both the screens o_1 and o_2 have centrally-disposed 30 openings so that the vapor from the cathode k may rise and strike the cooling element r while at the same time the arcs from the anodes unite and find their way to the cathode. The form shown in Fig. 7 is 35 similar to the form shown in Fig. 5 but there is provided a plurality of cooling elements r_1 , r_2 , and r_3 surrounded as disclosed by the concentric screens o_1 and o_2 . In the form shown in Fig. 9, the casing 40 is divided by partitions p so that a series of groups of anodes having their projecting ends d extending up therethrough is formed, these groups being indicated by the Roman numerals from I to 45 VI inclusive, and in Fig. 10 is shown the manner of connecting the six phases indicated by these groups.

It is sometimes desirable to introduce the anodes through the bottom of the casing and 50 to that end a form is shown in Fig. 11 wherein each anode has its leading-in wire extending through an insulating member i provided on its upper end with a hood h wherein the anode is located and these 55 hoods all face the axis of the casing g and are equi-distant therefrom so that the

arcs to the cathode k may be equal. This form may also be provided with cooling members r ; all of the cooling members shown being open at their upper ends 60 to the air as can readily be seen by reference to the figures.

Experience has demonstrated that the screens above described may either be constructed of a non-insulating material, as 65 metal, or of a suitable insulating material.

Having thus described the invention, what is claimed as new is:—

1. In a rectifier of the class described, a closed container of metal, a mercury cathode 70 in the bottom of said container, a plurality of anodes arranged circularly in said container and adjacent its side walls, a screen interposed between said anodes and the side wall and embracing said anodes, the lower 75 tapered end of said screen having a centrally disposed opening, said opening being directed toward the cathode.

2. In a rectifier of the class described, a closed container, a mercury cathode in the 80 bottom thereof, a plurality of anodes arranged around said container adjacent the wall thereof, and an insulating screen surrounding said anodes and provided with a constricted neck dipping into said cathode. 85

3. In a rectifier of the class described, a closed container, a series of anodes positioned adjacent the side wall of said container, a cathode, a cooling member, and screen means between said anodes and the 90 cathode and cooling member.

4. In a rectifier of the class described, a closed container, a series of anodes spaced around the side wall of said container, a screen surrounding said anodes and interposed between the wall and the anodes, said screen having a funnel-shaped bottom, a cathode immediately below the mouth of said funnel, a cooling member having an open end and depending from the top of said 100 container, and a screen surrounding said cooling member and open at the bottom, said screen being interposed between the anodes and the cooling member and both of said screens being of insulating material. 105

In testimony whereof I have affixed my signature in presence of two witnesses.

BÉLA SCHAEFER.
